UNITED STATES PATENT OFFICE.

WILLIAM GRUNOW, JR., OF WATERBURY, CONNECTICUT, ASSIGNOR TO AMERICAN RAILWAY SIGNAL COMPANY, A CORPORATION OF CONNECTICUT.

ART OF RAILWAY SIGNALING.

1,040,940.

Specification of Letters Patent.

Patented Oct. 8, 1912.

Application filed May 10, 1911. Serial No. 626,311.

To all whom it may concern:

Be it known that I, WILLIAM GRUNOW, Jr., a citizen of the United States, and resident of Waterbury, county of New Haven, 5 and State of Connecticut, have made a new and useful Invention in the Art of Railway Signaling, of which the following is a specification.

My invention is directed particularly to 10 improvements upon two inventions disclosed in prior patents granted on the 16th day of July, 1907 to Wesley T. Oviatt, Edward F. Latimer and William Grunow, Jr., No. 860,561 and to R. C. Cram and C. L. Graves, 15 No. 860,532, the essential points of novelty in the present instance being more especially directed to improvements upon the invention disclosed in Patent No. 860,561.

My invention has for its objects—First, 20 the rearrangement of the circuit relations of the controlling circuits and the operating and controlling electromagnets of such a system and in such manner that the operating electromagnets which set the signals are 25 located in series relation with each other and are adapted to be operated from opposite ends of the section, either upon the entrance or withdrawal of a car, said circuits being always normally open so that the elec- 30 trical energy is required only during the time that cars are passing over the protected section. Second, the provision of novel appliances for effecting in the simplest possible manner the certain closure of the controlling and operating circuits for definite times, no matter what may be the speed with which a car enters or leaves a section, through the agency of controlling electromagnets adapted to surely close the operating 35 circuits a sufficient time to enable the signal operating electromagnets to certainly effect the setting or release of the signals. Third, the provision of novel signal setting and signal locking mechanism for semaphores or like visual signals which shall be 40 absolutely positive in its action and shall be controlled by step by step mechanism adapted to rotate it in opposite directions and without any possibility of a failure 45 to act when either of the two operating electromagnets is energized. Fourth, the provision also, in addition to semaphores which shall indicate at each end of a protected section the condition thereof as relates to the 50 number of cars actually passing over the

same at any time, of illuminating visual signals or audible signals, or both, which shall indicate to a motorman as his car enters at either end the conditions which the visual semaphore signals indicate, and 60 shall also give warning to him and to others in the vicinity that the semaphores have either been properly set or that the failure of the same to be set has given him proper warning that he should not proceed until 65 the signals are properly displayed by the outward passage of any car which has preceded him. Fifth, the provision of means in connection with a safety system of signaling, whereby when the predetermined 70 number of cars which may at any time be permitted to travel in the same direction over a protected section has entered the same the signals will cease to work further—or those already set will cease to be 75 displayed—until one or more of the preceding cars has or have passed out of the section and in the proper direction, thus affording both a visual and an audible indication to the motorman and to others of the 80 fact that his car should not enter the protected section until the signal immediately in front of him shall have given indication that he may properly proceed. Sixth, the provision of means whereby the passage of 85 cars in a given direction may be continuous over a protected section so long as the signals of such section are made operative by reason of such entrance and in such manner as to show the motorman that he is 90 entitled to enter the section and that the maximum number of cars allowed to enter has not preceded him upon such section; the arrangement being such that when the maximum number has already entered the 95 section the signals will not operate and he will be required to back out, and under orders should not enter again until he is satisfied that a proper time has elapsed to allow him to properly enter and properly operate 100 the signals after one or more of the preceding cars has gone out of the section. Seventh, the provision of means for use in the operation of signals of the character referred to whereby there is absolutely no possibility of the signals being wrongfully operated so as not to show the proper condition of affairs either upon the entrance or the withdrawal of two cars simultaneously 105 at the opposite ends of the protected section; 110

the arrangement being such that no matter what may be the speed of either or both of the cars so entering or withdrawing at the same instant of time there is no possible chance that the signals either already set shall be disturbed, or those to be set shall be improperly set, thus making it absolutely certain that there never can be upon the protected section, if orders be obeyed, at any one time more than the maximum number of cars allowed to travel in the same direction; or an indicated condition other than the truthful indication that the section is fully occupied and the signals are properly set that only when the last car leaves at the outgoing end will it be made apparent that there are no cars preceding the next entering car, the arrangement of the circuits, control mechanism, and signal operating mechanism being such that the signals will always give the proper indication and under all of the conditions upon which cars travel over single tracks having the usual passing sidings. Eighth, to provide for use with railway safety systems of the type referred to a compound signal embracing two signals each adapted to be operated by independent operating mechanism so interconnected that each signal is made operative or displayed by its own operating mechanism whenever actuated and while so actuated the companion signal is released and concealed from view, the interconnecting mechanism being of such a nature that for the first impulse sent over the line the proper signal will be set and locked and that each succeeding impulse sent through the same electromagnetic apparatus will advance the locking mechanism so that after a signal is once set and locked by the transmission of a definite number of impulses it cannot possibly be released until the other mechanism which operates the other signal shall have been actuated by a like definite number of impulses; thereby assuring a proper signaling effect for the accumulation of cars in a protected section. Ninth, to provide means whereby when a car enters one end of a protected section of single track a danger signal will be set at the distant outgoing end by said car and simultaneously the signal control mechanism at that point will be so effected that an incoming car running in reverse direction cannot set any signal and the motorman will be warned by the signal already set that he must back out, and also that such backing out cannot affect the operation of any signal until the first car has left the section, either by advancing therethrough or by backing out. Tenth, to provide flash signals at either or both ends of a protected section of single track which will only operate on the entering of a car upon its proper siding when the section ahead is either unoccupied or is occupied by

any number of cars up to the maximum number allowed on the section.

For a full and clear understanding of my invention such as will enable others skilled in the art to construct and use the same, reference is had to the accompanying drawings, in which,

Figures 1 and 2 are diagrammatic views which when placed side by side with Fig. 1 upon the left illustrate in detail a single protected section of an electric railway provided with my novel system of signal operating and signal control devices; together with two line wires, a single trolley wire extending over the protected section, and side track trolley wires at each end thereof where single and two point switches are provided and adapted to be operated by the trolley wheel of a passing car in either direction. Fig. 3 is an enlarged part sectional, part side elevational view of my novel signal operating mechanism in the nature of step by step apparatus driven in opposite directions by either of two powerful electromagnets of the solenoid type, the signal or semaphore operating cam disks, however, not being shown in this figure. Fig. 4 is a plan view of the same apparatus as seen looking at Fig. 3 from the top toward the bottom of the drawings, the signal or semaphore operating cam disks being shown in this view, certain electrical circuit connections being also illustrated in connection with this part of the apparatus. Fig. 5 is a side elevational view illustrating the operative relations of the signal operating cam disks, the pivoted operating counter balanced semaphore operating levers connected in turn to the pivoted arms of the semaphores themselves, the latter being only partly shown; certain electrical circuit connections being also illustrated in connection with this part of the apparatus. Fig. 6 is a detail view of the signal operating mechanism illustrating one of the operating electromagnets; the signal operating cam disks and the shaft which carries the same being shown in elevational view; together with the differential gear mechanism through the agency of which the semaphores or signals are prevented from operating in the event of cars entering or withdrawing at opposite ends of a section at identically the same instant. Fig. 7 is a side elevational view of one of the signal boxes showing also the means of suspension of the same beside the roadway; together with the semaphores and signal light lenses inclosed therein. Fig. 8 is a side elevational view of the electro-magnetically controlled mechanism for effecting a definite time interval of closure of the circuits through the signal operating electromagnets or solenoids; and Fig. 9 is an end elevational view of the same mechanism as seen looking at Fig. 8 from left to right.

I will first describe the signal operating mechanism illustrated in detail in Figs. 3, 4, 5 and 6 and will then describe the controlling mechanism for effecting a definite time limit 5 of closure of the circuits to the operating electromagnets or solenoids illustrated in Figs. 8 and 9, after which I will describe the operation of the apparatus by referring to Figs. 1 and 2.

10 As above noted the apparatus disclosed in this application embraces signal operating and signal controlling mechanism designed to operate upon normally open circuits and made operative through the agency of switches actuated by the movement of a car trolley wheel much in the same manner as the signal apparatus is operated in the before-mentioned patent to Oviatt, Latimer and Grunow, Jr., it being understood that 15 these switches are provided with appliances adapted to assure a closure of the circuit through the control and signal operating electromagnets for a definite length of time sufficient to certainly actuate said electromagnets.

15 M, M¹ represent the signal operating electromagnets preferably of the solenoid type, as clearly illustrated on the left in Fig. 3, the same being provided with the well known form of magnetic casing and a non-magnetic ring at the base thereof for preventing the disk end 2 of the movable section of the core from sticking when drawn upward with a non-magnetic guide-rod 3 to which it is attached so as to slide through a tubular bearing in the stationary half of the core and a guide-way in the upper end of the frame, as clearly shown, 4 being a pivoted operating lever secured by a pin to the 20 rod 3 and provided with a pivoted spring pressed propelling pawl 5 and a locking pawl 5¹.

25 6 represents a stop pawl pivoted to the frame and connected by a spiral spring with the lever 4.

30 6¹ represents a holding pawl, and 7, 7, are toothed driving wheels journaled loosely on the driving shaft 8.

35 9 is a two-part arm keyed to the shaft 8 by a pin 10 and having on its opposite ends journal bearings for supporting two idle pinions 11, 11, the teeth of which are adapted to mesh with the teeth of crown gearing wheels 12, 12 located on the inner side faces of the toothed driving wheels 7, 7, said crown gear wheels and the pinions constituting what I term "differential gear" adapted to permit the shaft 8 to be rotated in either direction as a car enters or withdraws from either end 40 of any protected section; or, to prevent any rotation thereof should two cars enter or withdraw simultaneously and hence actuate the controlling switches, this apparatus being designed especially to prevent any possibility of operating the signals in the event

of such absolute simultaneous movement of cars.

45 It will be apparent on inspection of Figs. 3 and 4 of the drawings that the parts 4, 5, 5¹, 6 and 6¹ are duplicates for the two electromagnets M and M¹ and their toothed loosely journaled driving wheels 7, 7, the pawls 5, however, being adapted to individually rotate the shaft 8 in opposite directions, as will be more particularly described in connection with the description of the mode of operation.

50 13, 13 are two signal and semaphore operating cam disks both keyed to the shaft 8 and, therefore, rotatable in opposite directions therewith. These disks are provided respectively with semi-circular extended rims, as clearly illustrated in dotted and full lines in Fig. 5 and in full lines in Figs. 4 and 6, and are so interrelated that when one semi-circular extended rim is operating so as to lift its signal operating lever 14 through the agency of its companion operating pin 15, the other is not operating upon the other like parts of the companion semaphore, and 55 when the signals are at safety and no car upon the section, both of the operating pins 15, 15, and their corresponding signal operating levers 14, 14, are in the position shown in Fig. 6; that is to say, both in the depressed positions, and both of the semaphores W and R (see Figs. 5 and 7) in their released or safety positions.

55 16, 16 represent insulated contact plates carried by the arms 14 of the semaphore R, 100 their function being to close the circuit through stationary terminals 24, 24 of a conductor 21, as will be described later on.

60 18, 18 are metal arms secured by pins to the shafts 17, 17 which carry the sets of 105 pawls 6, 6¹ (see Figs. 4 and 5) and 19, 19 are bridging contact plates carried by said arms and adapted, when moved by the shafts 17, 17, to perform functions which will be described later on in connection with the description of the mode of operation and with similar parts operatively connected with the signaling mechanism, as clearly disclosed in Figs. 1 and 2 of the drawings.

65 Referring now to Figs. 8 and 9 I will describe the structural apparatus for effecting a definite time interval for closing the circuits to the signal operating electromagnets M and M¹, the same embracing in each instance an electromagnet S provided with a 115 pivoted armature lever a and a curvilinear pole piece p attached to the rear end of the core of the magnet with its free end in the magnetic field of the armature of the armature lever a, said pole piece and the core of 120 the electromagnet being secured to a standard f, the upper or curvilinear end of which supports a journal bearing for a rotatable momentum disk d provided on its inner face with an operating pin p¹ resting normally 125

against the curvilinear end of the armature lever a . This disk d is provided with a weight w for holding it in its normal position, and the extended shaft of the disk is 5 provided with an insulating sleeve adapted to rotate with the disk and carrying two bridging contact plates t and 27 , the contact plates t having normal contact with the two spring pressed terminals $26, 26$, the bridging contact plate 27 being adapted, 10 when the electromagnet is energized, to rotate the disk under the influence of the armature a and pin p through a definite space until the relatively broader bridging contact plate 27 makes contact with two spring 15 pressed terminals $28, 28$, s being a stop for the disk adapted to hold it against the influence of the weight w by reason of its contact with a lug e on the face of the supporting standard f . All of the conducting parts 20 of this device are effectually insulated, as shown, so as to adapt it for use with high potential circuits. The operation of this part of the apparatus will be disclosed in 25 connection with the description of the mode of operation.

Referring now to Figs. 1 and 2 there is shown diagrammatically on both figures one complete protected section embracing a trolley conductor T extending over the entire single track section, and a branch trolley conductor T^1 for a siding at each end; two 30 2-point switches sw, sw one at each end of the section, and two single point switches s^1w^1, s^1w^1 , one at each end of the section, all 35 of said switches being made operative through the agency of the trolley wheel as it passes—the two point switches in either direction and the single point switches in one direction only, dependent upon whether a car is 40 moving from right to left, east to west, or vice versa. $30, 30$ represent two line wire circuits extending over the protected section, the same being normally grounded at 45 both ends, through the signal operating electromagnets M, M^1 ; the controlling and operating circuits being all normally open at the switches adjacent to the trolley wire and its sidings, so that there is no possibility 50 of any of the signals being operated until the car shall have entered the protected section in either direction. The controlling circuits also are normally grounded, both at each end of the section through 55 rheostats R^h, R^h . I, I represent electric lamps for giving luminous signals for night use, said lamps being connected in circuit with conductors L^1, L^1 indicated in dotted lines and running to the necessary circuit 60 closing devices for effecting the closure thereof through the agency of the semaphores. I^1, I^1 represent incandescent flash light lamps adapted to be actuated when a car enters the protected section from either 65 end, so as to indicate to the motorman the

fact that it is proper for him to enter, the absence of the action of such flash lights being evidence to him that he should not enter. Said lamps also illuminate the semaphore arms at night when they are set. 70 The rheostats R^h, R^h are adjustable and are utilized for varying the resistance through the line and control circuits to suit the conditions of the sections to be protected, such variable resistances being necessitated by 75 reason of the fact that these protected sections often differ very materially in their length, cars often running on suburban roads for many miles on a single track and the sidings being located to suit the peculiar 80 conditions of the territory to be passed over. The curves in the roadway also often make it imperative that the protected sections shall be much shorter than in districts where the road passes over relatively level and 85 clear country.

It will be noted on inspection of Figs. 3, 4 and 5 that the operating electromagnets or solenoids M and M^1 which control the movement of the semaphores and their signals are so located relatively to each other and the toothed driving wheels $7, 7$ that through the agency of their step by step mechanism they may drive the shaft 8 and the signal and semaphore operating and locking cam disks $13, 13$ in opposite directions, dependent upon which electromagnet is energized; so that this must be borne in mind in describing the mode of operation in view of the diagrammatic dispositions of the like 100 parts illustrated in Figs. 1 and 2. Suppose now that the entire apparatus is as illustrated in said figures of the drawings and that no car is standing upon or passing over the protected section between the sidings in 105 said figures. As the car enters, therefore, from the right in the direction of the upper arrow, passing upon the siding, the trolley wheel actuates the switch sw closing the circuit from the branch trolley conductor T^1 by way of a branch conductor 21 , to stationary contact terminals 24 , and through the bridging contact plate 16 carried by the lever 14 of the red or danger semaphore R ; thence through time limit 110 control solenoid S on the left through the rheostat R^h to earth at E . This imparts a momentary rotary movement to the weighted momentum disk d and rotates the same in the direction of the arrow Fig. 2 from 115 right to left, breaking the circuit between the bridging contact plate t and the spring pressed terminals 26 ; at the same time closing a new circuit through the elongated contact plate 27 , stationary terminals 28 , so that current now flows for a prolonged 120 time interval by way of branch conductors L permanently connected with the trolley wire, one of the terminals 28 , through the contact plate 27 , the other terminal 28 , 125

130

through the line wire 30, the signal operating magnet M^1 at the incoming station, upper line wire 30 passing over the protected section, operating magnet M for the red signal or semaphore R , at the distant end, spring pressed terminals 26, bridging contact plate t , through the rheostat R^h to earth at E^1 . This prolonged impulse transmitted over the line causes the propelling pawl 5 to rotate the two cam disks 13 at the entering station from right to left in the direction of the arrow, so that the pin 15 of the signal operating lever 14 of the white semaphore W causes said semaphore to be raised and locked in its upper position as shown in dotted lines Fig. 2 and full lines Fig. 5, by reason of the cam action of the extended edge of the disk and will retain the signal in such locked position until the disks are rotated in a reverse direction. The same action caused the other disk 13 on the same shaft 8 for the red or danger semaphore R at the ingoing end to be rotated in the same direction, thus removing the eccentric portion of its disk 13 one step from the operating pin 15. The two disks 13 at the distant or outgoing end were likewise rotated one step to the left in the direction of the arrow through the influence of the operating solenoid or electromagnet M and the red or danger semaphore R was lifted into the position shown in dotted lines; while the eccentric part of the disk 13 for the white semaphore was removed one step to the left and away from its operating pin 15. Consequently, the white or caution semaphore was displayed at the incoming end Fig. 2 and the red or danger semaphore was displayed at the outgoing end in Fig. 1 and both semaphores temporarily locked in such displayed positions. At the same time, the circuit was temporarily closed at the incoming end Fig. 2 through the contact plates 16¹, 16² carried by the arm of the white semaphore W to contact plates 16³ and 16⁴ thereby temporarily closing a lighting circuit from the trolley conductor T through branch conductor L to and through additional branch conductors L^1 indicated in dotted lines, three lamps I on the right behind the white glass lens, thus giving a white light indication, thence through the two lamps I^1 on the right by conductor 31 to ground at E , thus illuminating the white semaphore W , thereby giving two visual indications—one from the lamps I and the other from the reflected light at night time upon the semaphore arm W . Any subsequent car, therefore, on entering and operating the switch sw , Fig. 2, will cause identically the same movement of the signal controlling and signal operating magnets which were actuated by the entrance of the first car, but in view of the fact that the signals have been set and locked by any preceding car and the lamps left glowing, I provide an additional means of warning the motorman of the incoming car of the fact that the section preceding him is occupied by momentarily interrupting the lamp circuits between the bridging contact plate 19 in the lamp circuit L^1 , it being apparent that when the electromagnet M^1 is again actuated the circuit will be interrupted between the contact plates 19 as the step by step mechanism is actuated, thus momentarily flashing the lamps. This arrangement of circuits, of course, is provided for all four of the operating magnets, as is clearly illustrated, and gives absolute assurance of the operation, and also warns the motormen and the public of such effective operation. The same impulse which set and locked the signals at the incoming station also, as before stated, set and locked the red semaphore R at the outgoing station in its upper or displayed position, as indicated in dotted lines, and also closed a circuit from trolley wire T and the conductor L at that point indicated in full lines, and L^1 indicated in dotted lines, the three lamps I on the extreme right, the two lamps I^1 on the extreme left, downward by conductor 31 to earth at E^1 , thus giving a reflected light upon the red semaphore R and a red light through the red lens for that semaphore, so that now there is a danger warning set and locked for incoming cars at the outgoing end in Fig. 1. It will be noted that when the red semaphore R was lifted into its exposed and locked position by the disk 13 the circuit was broken between the contact plate 16 and the contact terminals 24 which connect with the conductor 21 running to the switch sw adapted to be controlled by the movement of incoming cars from the left; so that should a motorman from the left fail to observe the red signal and inadvertently pass such switch no results will follow; likewise no results will follow on his backing out because the conductor 22 which connects that switch with the operative parts of the system is now open at the plates 16 and 16² because of the fact that the white semaphore at that station is in its lower or unexposed position, so that he simply backs out and awaits further developments. As the motorman entered on the right and observed that the white semaphore was set for him he realizes the fact that the section is safely clear and he may proceed. He also knows that the danger signal has been set at the outgoing end because the white semaphore has been set at the ingoing end, the operating electromagnets being in series; he, therefore, proceeds with the full knowledge that he has the right of way. When the car passes out at distant station the trolley wheel operates the single contact switch s^1w^1 at that point and closes the trolley circuit through 130

6

the conductor 23, through the terminals 24¹ and contact plates 16 carried by the arm of the red semaphore R, control magnet S on the right at the outgoing end to earth at 5 E¹, thereby rotating the momentum disk d and causing it to momentarily break the circuit between the terminals 26 and the bridging contact plate t and to bring the elongated contact plate 27 into electrical contact with the terminals 28 for a definite time interval, thereby closing the circuit from the trolley conductor T by the conductor L on the left to and through bridging contact plate 27, terminals 28, line wire 30, electromagnets M¹ at the outgoing end, the lower one of the line wires 30 extending over the section to the operating magnet M at the distant station in Fig. 2; thence to the spring pressed terminals 26 on the extreme right of 10 the time limit control mechanism, bridging contact plate t carried thereby, rheostat R^h to earth at E; thus rotating the shaft 8 and both of the disks 13 one step to the right so that the pin 15 for the red semaphore assumes its original or starting position ready 15 to lift the semaphore when the proper impulse is transmitted from the distant end of the section in Fig. 1. At the same time, of course, the pin 15 has been released from its 20 lifting and locking relation to the cam disk 13 for the white semaphore W at the distant end and it is allowed to fall into its concealed position indicated in full lines, so that the circuits for the lights I and I¹ are 25 broken and the signaling apparatus at that station is all in normal condition, indicating that there is no car upon the section. As the car proceeds, therefore, over the siding track and as it passes out of the same it will 30 encounter another two-point contact switch, not shown, but like the two point contact switch shown in Fig. 2 where corresponding appliances are provided for a single track section in advance and where the same precautions will be observed as were observed in 35 the entering of the section from which the car has just passed, as has been described, it being understood that each single track section is provided with two sets of appliances 40 having the apparatus and circuit connections 45 illustrated in the drawings, Figs. 1 and 2, and as hereinbefore described. Suppose now that a number of cars follow the car already referred to before the same leaves the protected section. It will be seen that the apparatus herein disclosed is capable of accommodating 16 cars on a section, there being 16 teeth for each of the operating wheels 50 7 so that any number of cars up to 16 may 55 enter and each time a car enters exactly the same operation will ensue as has been described, except, it will be noted, that as each car enters the cam disk 13 which operates the white semaphore W will be rotated forward 60 65 step by step so that when the 16 cars are in

the section this semaphore will be locked permanently in exposed position and the lamps I and I¹ on the right will be permanently displayed or until all of said cars have passed out of the section, and for like 70 reason the red semaphore R at the outgoing end will be permanently locked in displayed position and the red lamps I on the right and the lamps I¹ on the left permanently displayed, or until the last of the 16 cars has 75 passed out in the same manner as the first car was described as having passed out. Each outward passage, however, will rotate the two disks 13 to the left one step in the same manner as these disks were rotated when the 80 first car was described as having passed out, so that when they all have passed out the apparatus will assume the condition shown in full lines in the drawings. Of course, the number of cars which may be permitted 85 upon any section will be limited to the number of teeth in the driving wheels 7 and these may be varied at will.

Suppose now that after 15 cars have entered and that the last car to enter for some 90 reason backs out before any of the other cars have passed out—or even after any or all of them have passed out. In this event the switch sw is operated by the trolley wheel from left to right, closing a circuit 95 from the trolley conductor T¹, by way of conductor 22, the right and left hand terminals of 16², contact plates 16² carried by the arm of the white semaphore W, conductor 22 to the lower right hand control 100 electromagnet S¹, through the rheostat R^h to earth, thus operating the time limit control magnet and causing its armature A to rotate the momentum disk d from right to left, momentarily breaking the circuit between the terminals 26 and the bridging contact plate t and simultaneously closing the circuit between the elongated contact plate 27 and the stationary terminals 28, thereby closing a circuit from the trolley 110 wire T by the conductor L, terminals 28, contact plate 27, line wire 30, through the operating electromagnet M of the red semaphore, through the operating electromagnet M¹ of the white semaphore at the 115 distant station, terminals 26, bridging contact plate t, by rheostat R^h to earth at E¹. This prolonged impulse, therefore, rotates the two cam disks 13 at the incoming station one step to the right in the 120 direction of the arrow, thereby lowering the white semaphore at the incoming station and restoring the disk 13 for the red semaphore at the incoming station with the pin 15 in operative relation to the proper cam 125 disk, the movement of the like disk at the outgoing station being the reverse of that by the impulse transmitted when the car entered the section, thus releasing the red semaphore and restoring the cam disk 13 130

with the pin 15 in operative relation therewith, so that all of the apparatus stands now in its normal position, the same as though the car had not entered, and all of the signals and lamps are, therefore, in normal or safety condition with no current flowing in the system. Suppose now that 16 cars, the limit number, have all entered the protected section and that a car following 10 should enter on the right. In this event attention is directed to Fig. 5 of the drawings and to the fact that when the cam disks have been rotated by the entry of cars through practically 180° the pin 15 which 15 controls the movement of the red semaphore at the incoming station, comes into contact with a cam-like elevation 20 which is sufficiently high to break the circuit between the contact terminals 24 and the contact 20 plates 16 carried by the corresponding red semaphore arm R, thereby permanently breaking the circuit to the conductor 21 running to the incoming switch sw so that no effect will be or can be had upon the signals 25 by cars entering in this direction until one or more of the 16 cars already entered shall have passed through. He then simply awaits the indication by the signals to note when he may proceed. Therefore, as the 30 cars pass out the cam disks will be successively rotated in the proper direction and the mechanism ultimately put in its normal condition of safety. Under no circumstances, however, is it possible—if he obeys 35 orders—that he can rightfully proceed until he shall have received a proper indication that all of the cars have passed out; or that the limited number of 16 cars are not in the section. Suppose now that the protected 40 section is clear and that two cars enter in opposite directions and at such time that both of the two point switches at the opposite ends of the protected section are actuated at identically the same instant of time. 45 In this event reference is had to Figs. 4 and 6 of the drawings and it will be noted that when such simultaneous entrance of cars occurs the electromagnets M and M¹ at the opposite ends of the section will be simultaneously actuated, as will be apparent on tracing out the circuits from the two switches sw in opposite directions, as indicated by the upper arrow on the right and lower arrow on the left pointing in opposite 50 directions. When this occurs and the proper magnets are energized the two step by step mechanisms actuated by the two electromagnets will act simultaneously and the differential gear will obviously impart 55 no motion in either direction to the disks 13 so that the cam effect thereof will be null and no signals will be operated at either end and both motormen will be warned of the fact that the signals have failed to operate so 60 that they must both withdraw their cars; 65

therefore, the one who now enters first will set the signals in warning to the other and he may properly proceed until he passes out at the distant end. It will also be apparent that the differential action of the gearing 70 illustrated in Fig. 6 will permit either of the disks 13 to be operated by its proper operating magnet when such magnet is operated alone, in which event the idle pinions 11 act as fulcrumed levers to impart 75 the proper motion to the disk it is intended to rotate.

It is to be observed that with the arrangement of circuits and control and operating mechanism disclosed in the drawings and hereinbefore described it is not possible for motormen, if they follow orders, to wrongfully enter a section if they observe the signals as disclosed when they enter, no matter in which direction the cars may be traveling; nor is it possible for more than the limited number of cars to enter a section without violating orders. Furthermore, it is to be noted that the time limit control mechanism illustrated in Figs. 8 and 9 of the drawings is of such a nature that no matter what the speed of a car may be when entering a section or passing out of the same in either direction this time limit mechanism will surely establish an interval of closing of 85 sufficient length to effectually energize the necessary electromagnets either for control or for the operation of the signals. 90

In the practical use of the invention hereinbefore described and illustrated in the accompanying drawings I propose to utilize time limit mechanism in connection with the trolley actuated switches like that disclosed in patent to Oviatt, Latimer and Grunow, Jr., but preferably like that described in a pending application filed by me on the 10th day of May, 1911 and bearing Serial No. 626,312, such time limit mechanism making it absolutely sure that the circuits will be closed from the trolley wire or from any 100 other source of electrical energy which may be utilized for a sufficient length of time to assure the operation of both the signal control and signal operating electromagnets. I further propose for certainty of operation to 105 inclose not only main line circuits 30, 30, but all of those conductors leading from the trolley wire or source of electrical energy to the signal boxes in iron or other metal conduits and to connect the same with earth, 110 either with the track rails or in any preferred manner, such conductors being well insulated, my object in this particular being to absolutely prevent any possibility of operation of the apparatus other than through 115 the current from the source of electrical energy utilized to that end, such as the trolley wire or other supply that is to be used, the signal boxes also being connected to earth by 120 conductors, thus avoiding any possibility of 125 conductors, thus avoiding any possibility of 130

wrongful operation due to induced currents, leakage currents, or from any extraneous source of electrical energy, or from lightning.

5 Obviously a number of the features of my invention may be utilized in other systems of signaling; for instance, the feature of the locking of a signal in a definite or displayed position during the time that a plurality of 10 cars are passing over a protected section, this feature being especially important in that it absolutely assures that the signal cannot be returned to safety until all of the cars have passed out of the section, either in 15 advance or by withdrawal. Obviously also the combination of operating electromagnets or electromotive devices generally for manipulating or operating signals when combined with electromagnetically con- 20 trolled time limit mechanism as I have combined these features may be utilized with other systems, and my claims are also generic as to these features and as to the use of the devices in railway signal appliances generally; or as to the use of such devices as I 25 have described in connection with signal appliances in the arts generally.

Having thus described my invention what I claim and desire to secure by Letters Patent of the United States is—

1. In a railway block-signal system, the combination of two signals at each end of a block, actuating electro-magnets for said several signals, a main circuit, two line 35 wires extending throughout the block, each grounded in series with an electro-magnet at each end thereof, circuit controllers for breaking such grounds and establishing electric connection between the main circuit 40 and line wires, electro-magnets for actuating said circuit controllers, branch circuits for said controller electro-magnets, and switches actuated by the cars for closing said branch circuits.

45 2. In a railway block-signal system, the combination of two signals at each end of a block, actuating electro-magnets for said several signals, a main circuit, two line wires extending throughout the block and 50 each normally grounded through an electro-magnet at each end thereof, circuit controllers for breaking such grounds and establishing electrical connections between said main circuit and line wires, and means actuated by the cars for operating said circuit controllers.

55 3. In a railway block-signal system, the combination of two signals at each end of a block, actuating electro-magnets for said several signals, a main circuit, two line 60 wires extending throughout the block and

each normally grounded through an electro-magnet at each end thereof, circuit controllers, electro-magnets for actuating said controllers to break such grounds and establish 65 electrical connections between said main circuit and line wires, branch circuits for said controller electro-magnets, and switches actuated by the cars for closing said branch circuits.

70 4. In a railway block-signal system, the combination of two signals at each end of a block, actuating electro-magnets for said several signals, two main line circuits, each in series with an electro-magnet at each 75 end of the block, controller electro-magnets, and time interval mechanism actuated by said controller magnets for maintaining said main line circuits closed during predetermined, uniform periods of time.

80 5. In a railway block-signal system, the combination of two signals at each end of a block, actuating electro-magnets for said several signals, two main line circuits, each in series with an electro-magnet at each end 85 of the block, time interval mechanism for maintaining said main line circuits closed during predetermined, uniform periods of time, controller electro-magnets for actuating said time interval mechanism, branch 90 circuits for said controller electro-magnets, and switches actuated by the cars for closing said branch circuits.

95 6. In a railway block-signal system, the combination of two signals at each end of a block, actuating electro-magnets for said several signals, a main circuit, two line wires extending throughout the block, each in series with an electro-magnet at each end 100 thereof, controller electro-magnets, and time interval mechanism actuated by said controller magnets for maintaining said line wires in electrical connection with said main circuit during predetermined, uniform 105 periods of time.

110 7. In a railway block-signal system, the combination of a pair of distinctive signals, differential gear and intermediate mechanism for selectively shifting said signals respectively according as the mechanism is moved in one direction or the other, a pair 115 of magnets and intermediate mechanism for actuating said differential gear in opposite directions, and means controlled by the cars for operating said electro-magnets.

In testimony whereof I have signed my name to this specification in the presence of two subscribing witnesses.

WILLIAM GRUNOW, JR.
